UNITED STATES PATENT OFFICE.

GEORGE W. PRISBREY, OF ST. GEORGE, UTAH, ASSIGNOR OF ONE-SIXTH TO BRIGHAM CARPENTER AND ONE-SIXTH TO ROBERT FAWCETT, OF ST. GEORGE, UTAH.

PORTABLE METAL-TURNING LATHE.

1,352,380.

Specification of Letters Patent.

Patented Sept. 7, 1920.

Application filed December 11, 1919. Serial No. 344,013.

To all whom it may concern:

Be it known that I, GEORGE W. PRISBREY, a citizen of the United States, residing at St. George, in the county of Washington and State of Utah, have invented certain new and useful Improvements in Portable Metal-Turning Lathes; and I do declare the following to be a full, clear, and exact description of the invention, such as will enable others skilled in the art to which it appertains to make and use the same.

My invention relates to improvements in portable lathes and more particularly to one of novel form well adapted for use by gunsmiths in reducing metal rods for numerous purposes, such as forming screws therefrom.

The principal object of the invention is to provide a simple, inexpensive and easily operable lathe which may be used either by holding it in a vise and turning the work with a pipe wrench or the like, or by holding the work stationary and turning the lathe, the arrangement being such as to permit the turning of rods having different diameters and lengths.

Another object is to provide a lathe of the type set forth having feed means of novel form for properly advancing the cutter to the work, means being provided however for throwing said feed means out of play when the tool is to be used for cutting off the work or for finishing an end or shoulder.

Still further objects are the provision of simple and effective means for clamping and centering the work and for holding it in proper relation with the cutter.

With the foregoing in view, the invention resides in the novel construction and arrangement of parts hereinafter described and claimed, the descriptive matter being supplemented by the accompanying drawings.

Figure 1 is an end view of a lathe constructed in accordance with my invention.

Fig. 2 is a transverse section on the plane of line 2—2 of Fig. 1.

Fig. 3 is a longitudinal section as indicated by line 3—3 of Fig. 1.

Fig. 4 is a side view.

Fig. 5 is a horizontal section on the plane of line 5—5 of Fig. 2.

Fig. 6 is a perspective view of the cutter carrying slide.

Fig. 7 is a perspective view of a bushing 55 used when turning rectangular work.

In the drawings above briefly described, the numeral 1 designates a preferably rectangular head formed of a single metal block provided with a central work receiving opening 2. Two opposed corners of the head are preferably provided with threaded sockets 3 by means of which a pair of handles (not shown) may be attached for the purpose of turning the head upon the work when this is advisable. At one side of the opening 2, the head 1 is provided with a longitudinal groove or guide-way 4 having undercut sides, and a dove-tail base 5 on a slide 6, is received in said groove or guide-way. The slide 6 carries a cutter 7 extending into the opening 2, and by means of a suitable screw 8, said slide may be adjusted for turning the work to different diameters. The cutter 7 by preference projects adjustably through a transverse opening 9 in the slide 6 and is provided on its outer end with a crosshead 10 through which threaded studs 11 pass slidably. These studs project rigidly from the slide 6 and are provided with nuts 12 bearing against the crosshead 10, and by adjusting these nuts, the cutter may be set in the most advantageous manner. Another guide-way 13 is formed in the head 1 and preferably extends parallel with the guide-way 4, said guide-way 13 receiving a slide 14 whose inner end is shaped to form a shoe 15 for contact with the work to counteract the thrust of the cutter 7. Any appropriate screw or the like 16 may be provided for adjusting the slide 14 according to the diameter of the work, and although I have shown this slide positioned at right angles to the cutter 7, it might well be aligned with said cutter. Similarly, although I have shown and described a number of preferred details of construction with reference to the head 1, the cutter 7 and the adjusting means for said cutter, other features of construction might be used in some instances.

In connection with the features above described or their equivalents, I prefer to employ novel feed means for the work which consists briefly of a feed nut 17 carried by the head 1, a sleeve 18 threaded through said nut adapted to receive the work 19, and means for centering and clamping the work in said sleeve. By this arrangement, when

100

105

the work 19 and the head 1 are relatively turned, the cutter 7 is properly advanced along the work to remove a shaving of thickness equal to the pitch of the screw threads 20 by means of which the nut and sleeve are connected. At times, for instance when finishing an end of the work or a shoulder, the feed should be discontinued and the head merely allowed to turn around the work, or vice versa, and in order that this may be done, I provide means for holding the nut 17 and sleeve 18 against relative turning, but allow the head and nut to turn with respect to each other. To attain this end, the nut 17 is swiveled on the head 1 and means is provided to normally lock said nut for movement bodily with the head, but for releasing said nut when desired.

An annular internally channeled bearing 21 is preferably provided to surround the nut 17 and receive the relatively narrow peripheral edge 22 thereof, and by means of suitable spacers 23, the bearing 21 is rigidly carried by the head 1 in such position as to align the sleeve 18 with the opening 2. A set screw 24 is shown threaded through the bearing 21 and receivable in an opening 25 in the nut 17 for normally holding the latter against turning with respect to said bearing, but when this screw is released, free relative movement of said nut and bearing is permitted.

To hold the nut 17 and the sleeve 18 against relative turning when said nut is released to turn in its bearing 21, I prefer that said sleeve 18 be provided with a stop 26 to abut said nut, and this stop is in most instances in the form of an external circumferential rib on the sleeve. When the stop 26 and nut are in contact with each other and screw 24 is released to allow turning of the nut 17 with respect to the bearing 21, the work and the head 1 may be relatively turned to move the cutter continually over the same path without feeding it longitudinally of the work. This is advantageous in finishing shoulders which have been turned, or for truing an end of the work. When turning the work down however or cutting threads thereon, the bearing 21 and nut 17 are secured against relative movement and thus any turning of the work within the head 1, or the head upon the work, will cause the nut and the sleeve 18 to properly feed the cutter to the work.

The means for centering and clamping the work in the sleeve 18 may well vary, but is preferably constructed as follows: Opposed lateral arms 26 are formed on the sleeve 18 and are provided with longitudinal guideways 27 in which sliding jaws 28 are mounted. The outer ends of the arms 26 are provided with sockets 29 in which heads 30 are swiveled, said heads having bores 31 in which stems 32 are threaded, said stems be-

ing carried by the jaws 28. The jaws in question may well be held in their guideways 27 by a detachable plate 33 and this plate may well carry lugs 34 received in grooves 35 in the heads 30, said lugs and grooves serving to prevent removal of said heads from the sockets 29.

In describing the operation, although the work can be held and the lathe rotated, we will assume that the head 1 is clamped in a vise and that a pipe wrench or other suitable tool is employed for rotating the work 19. This work is inserted in the sleeve 18 and is centered and clamped therein by the jaws 28 which are operated by turning of the heads 30. If the work is to be turned down or if threads are to be chased thereon, the feed nut 17 is held with respect to the head 1, with the result that turning of the work threads the sleeve 18 through said nut and thus properly advances the work to the cutter, adjustment of the latter having been previously effected. If the tool is to operate on a portion of the work greater in length than the threaded part of the sleeve 18, this sleeve may be unscrewed from the nut after performing part of the work and then advanced along the latter by loosening the jaws 28. When these jaws are again tightened, the tool may be operated for further cutting.

Whenever the feed is to be discontinued, the screw 24 is released and by then threading the sleeve 18 into the nut 17 until the stop 26 abuts said nut, the work, its carrying sleeve 18, and the nut in question may rotate as one unit and thus the tool and work will not be relatively shifted.

When turning square stock, the bushing illustrated in Fig. 7 may be inserted in the opening 2, said bushing being provided with a cylindrical outer surface 35 for contact with the shoe 15 and with a rectangular opening 36 to receive the work.

The device is comparatively simple and inexpensive, may be used to great advantage for numerous purposes, and is desirable in every way, and since probably the best results may be obtained from the details disclosed, they may well be followed if desired. I wish it understood however that within the scope of the invention as claimed, numerous minor changes may well be made.

I claim:

1. In a metal turning lathe a head having therethrough a work-receiving opening, a cutter carried by said head adjacent said opening, spacers extending rigidly from said head around the opening thereof, an annular internally channeled bearing carried rigidly by said spacers in spaced relation to said head, a substantially flat feed nut rotatably mounted in the channel of said bearing in alignment with said opening, a set screw carried by said bearing for hold-

ing said feed nut against turning when required, a sleeve threaded through said nut, a shoulder on said sleeve to abut said nut and hold the sleeve and nut against relative turning when the latter is released for rotation within said bearing, and means for centering and clamping the work in said sleeve.

2. In a metal turning lathe, a head having therethrough a work receiving opening, an adjustable cutter and an adjustable work guiding shoe carried by said head and ex-

tending into said opening, a feed nut carried by said head, a sleeve threaded through said nut, outstanding arms on said sleeve having 15 longitudinal guide-ways, said arms having sockets, work centering and clamping jaws 20 slideable in said guide-ways and having threaded stems, and heads swiveled in said sockets and having bores in which said stems are threaded.

In testimony whereof I have hereunto set my hand.

GEORGE W. PRISBREY.
